Primary Examiner—Prabhakar G. Deshmukh
Attorney, Agent, or Firm—Stevens, Davis, Miller & Mosher

[57] CLAIM

The ornamental design for a basket, as shown and described.

DESCRIPTION

FIG. 1 is a front, top and left-side perspective view of a basket showing my new design;
 FIG. 2 is a front elevational view;
 FIG. 3 is a rear elevational view;
 FIG. 4 is a right side elevational view;
 FIG. 5 is a top plan view;
 FIG. 6 is a bottom plan view thereof; and,
 FIG. 7 is a back, top and right-side perspective view of a basket showing my new design.
 The left side view is the mirror image of the right side view.
